OIL-BURNER.

1,076,327.

Specification of Letters Patent. Patented Oct. 21, 1913.

Application filed November 9, 1912. Serial No. 730,463.

To all whom it may concern:

Be it known that we, L. B. Strow and THOMAS E. McMILLAN, citizens of the United States, residing at San Antonio, in 5 the county of Bexar, State of Texas, have invented a new and useful Oil-Burner, of which the following is a specification.

The present invention appertains to oil or hydro-carbon burners, and aims to provide a 10 burner of this character which is applicable to various stoves, furnaces, boilers, heaters or the like so as to produce a high degree of combustion or a maximum heating effect with a minimum consumption of fuel.

15 It is also the object of the present invention to provide a hydro-carbon burner of novel and improved construction, and to provide a burner of this character which shall be simple, durable, compact, and inexpensive in its construction, as well as being efficient, and economical in its use.

To the above and other ends, which will appear as the description proceeds, the invention resides in the combination and arrangement of parts and in the details of construction hereinafter described and claimed, it being understood that changes in the precise embodiment of the invention herein disclosed can be made within the scope of what 20 is claimed without departing from the spirit of the invention.

The preferred embodiments of the invention have been illustrated in the accompanying drawing, wherein like reference characters have been employed to denote corresponding parts, and wherein:—

Figure 1 is a perspective view of the preferred form of the invention, parts being broken away. Fig. 2 is similar view of the 40 variations, parts being broken away. Fig. 3 is a vertical central section of one of the burners proper illustrated in Fig. 1.

Referring in detail to the drawing, the 45 present invention embodies as its essentials, a double burner 4 wherein each burner proper includes a gasifying or generating coil 5. A heating pipe 6 is attached to each coil and is curved so as to project across the 50 path of the products of combustion, the two heating pipes 6 passing out through the side of the fire-box or through the fire-box door, as indicated by the numeral 7, it being understood that as illustrated, the double 55 burner is applied to an ordinary cook stove and is seated within the firebox or combust-

tion chamber. The supply or feed pipes 8 are attached to the other ends of the respective heating pipes 6, and extend to a double valve 9, from whence, the supply of feed pipes are merged together into a single or unitary pipe 10 extending to the tank or can 11 for containing the oil or other liquid fuel.

In the form illustrated in Fig. 2, the double burner 4' comprises two coils 5' which are of a different configuration than the coils above described, the heating pipes 6' extending along the path of the products of combustion to the stove pipe, and extending up the stove pipe to a suitable point, from whence, they extend to the exterior. The supply or feed pipes 8' are each provided with a suitable controlling valve 9' and merge into a single or unitary pipe 10' extending to the tank or can 11'.

From the above, it will be manifest that the number and configurations of the burner coils will depend on the character of the stove, burner, or the like, and that the heating pipes may be passed through the path of 75 the products of combustion in any suitable or preferable manner.

In the former burner, designated by the numeral 4, the coil 5 is of frusto-conical form, whereas in the burner 4', the coil 5' 85 consists in a plurality of spaced parallel portions connected by bends. The former coil is preferable when the burner is to be employed in connection with a stove, heater or the like, whereas the latter form of coil is 90 preferable for use in furnaces, or for other like purposes wherein a greater amount of heat is required. In the hereinafter description, the details of the former burner are elicited, although it is understood that said 95 description will apply, so far as it appertains, to the other or second form of burner.

The burner 4 comprises a hollow base 12, preferably in the form of a casting, although it may be fashioned in any other manner as 100 will be apparent to the mechanic. The base as illustrated is of elongated or somewhat elliptical contour, although it is understood that the particular size and form of the base will depend upon the number of burners employed, whether single, double, treble or greater. This base 12 provides an air chamber for supplying the air for supporting combustion, the bottom of the base being open so as to communicate with the ash pit, 110

or any other underlying compartment, so as to communicate either directly or indirectly with the atmosphere. The sides of the base have been designated by the numeral 13, the 5 same being formed with a peripheral shoulder 14 and extending slightly above the top 16 in order to provide a marginal or peripheral flange 15 for the top. This flange 15 prevents waste oil, soot, or other extraneous 10 matter deposited on the top of the base from running over the sides thereof, thereby retaining the same on the top, from whence it may be removed when necessary.

The top of the base is provided with an 15 opening 17 for each burner, and with a tapered collar 18 around each opening. This collar 18 is provided with diametrically opposite recesses or openings 19, which extend throughout the length of the collar. 20 The top 16 is also provided with an integral member 20 extending diametrically across the opening 17 between the recesses 19 of the collar, said member 20 having its intermediate or central portion enlarged so as to 25 provide a circular portion 21 concentric with the opening and collar. The member 20 is also provided with upstanding flanges 22 along its edges thereby providing a channel, the intermediate portion of which is enlarged into a cup 21. The collar 18 is also 30 provided with a pair of diametrically opposite notches 23 in its upper edge, the said notches being arranged at quadrature to the recesses 19, or being arranged on a line at 35 right angles to the line connecting the recesses.

The top of the base is provided with an annular upstanding flange 24 surrounding and spaced from each collar 18 and forming 40 a channel around the collar communicating with the channel 20.

The lower end of the gasifying or generating coil 5 is bent to extend diametrically of the coil and rests or seats within the 45 notches 22 so as to cross over the channel 20 at right angles therewith. The inner end of the coil is also provided with an upper outlet aperture 25, which is directed axially through the coil, the cup 21 being disposed 50 directly beneath the outlet 25. The said cup therefore provides a priming cup for the coil, it being noted that the fuel which is permitted to drip into the cup 21 may follow the channel 20 to its ends and then into the 55 channel formed by the flange 24 so as to surround the collar, in order that when the fuel is ignited, the coil may be given an initial heat in an effective manner. The flange 24 also prevents the fuel from spreading 60 over the surface of the top of the base, and constrains it to remain in proximity to the collar and within the channel 20 and cup 21. The upper end of the coil is also bent to pass 65 diametrically of the coil or over the coil, and a reflector 26 is suspended or hung from

the upper end of the coil axially over the outlet 25. The reflector 26 is in the form of a disk, and its lower side or bottom is concaved, as designated by the numeral 27, and the top is provided with an ear 28 for engaging the upper end of the coil. The lower convolution of the coil 5 surrounds the upper end of the collar 18 and the coil rises from the collar, the inner end of the coil being closed by a cap, plug or the like.

In operation, the fuel is permitted to flow into the coil through the heating pipe so as to drip from the outlet 25 into the priming cup 21, in which event, the fuel in the priming cup is ignited for giving the initial heat 80 to the gasifying or generating coil. The coil in being heated will start the generation or vaporization of the fuel so that the resulting gas will be discharged from the outlet 25 axially of the coil. The gas in being 85 ignited will direct the flames axially upward through the coil so as to strike the reflector 26, from which the flames will be directed radially and downwardly toward the various convolutions of the coil. The coil is 90 thus continually heated in an effective manner so as to continue the generation of the fuel and the heating pipe lying in the path of the products of combustion will become heated as the combustion progresses so that 95 the fuel will thus be given an initial heat as it passes through the heating pipe to the coil, which will decrease the amount of heat necessary for the generation of the fuel within the coil. The fuel may thus be generated or vaporized effectively for producing a high degree of combustion. The reflector 26 will also become heated and in becoming highly heated, has the tendency to consume extraneous particles in order that 100 the deposit of soot may be reduced to a minimum. The air for supporting combustion is supplied upwardly from within the base 12 through the opening 17 in its top, so as to pass upwardly into the coil around the 105 outlet 25.

From the foregoing, taken in connection with the drawing, the advantages of the present burner will be manifest to those versed in the art, it being noted that this burner provides for high efficiency in the use thereof, and is so constructed as to meet with the requirements and to carry out the objects aimed at satisfactorily.

It is desirable to run suitable rods or 115 wires through the coils and through the fuel heating pipes to regulate the flow of fuel and gas and in order to prevent to a certain extent, the gas from expanding back into the pipe or reservoir, the said rods or wires 120 also assisting in the gasifying of the fuel.

Having thus described the invention, what is claimed as new is:

1. In a hydro-carbon burner, a hollow base having an opening in its top and a

channel spanning the opening, and a gasifying coil over the said opening, the inner end of the coil projecting over the said opening at quadrature to the channel and having an outlet directed through the coil, the outlet being disposed above the channel in order that the fuel may drip into the channel.

2. In a hydro-carbon burner, a hollow base having an opening in its top, a collar around the opening, and a channel spanning the opening, and a gasifying coil supported by the collar and having its inner end extending diametrically through the collar at quadrature to the channel, the inner end of the coil having an outlet directed through the coil, the outlet being disposed above the channel in order that the fuel may drip into the channel.

3. In a hydro-carbon burner, a hollow base having an opening in its top, a collar around the opening and a channel in the opening communicating through the collar and being formed with a priming cup, and a gasifying coil supported by the collar and having its inner end extending diametrically through the collar, the inner end of the coil having an outlet above the priming cup and directed through the coil.

4. In a hydro-carbon burner, a hollow base having an opening in its top, a collar around the opening, and a channel extending across the opening, and a gasifying coil supported by the collar, the inner end of the coil, the collar having openings at the end of the channel and the channel being enlarged below the outlet to provide a priming cup.

5. In a hydro-carbon burner, a hollow base having an opening in its top, a collar around the opening, and a channel extending across the opening, and a gasifying coil supported by the collar, the inner end of the coil projecting diametrically through the collar and having an outlet directed through the coil, the collar having openings at the end of the channel and the channel being enlarged below the outlet to provide a priming cup, the top of the base having a channel surrounding the collar and communicating with the ends of the aforesaid channel.

6. In a hydro-carbon burner, a hollow base having an opening in its top, a collar around the opening, and a channel extending across the opening, and a gasifying coil supported by the collar, the inner end of the coil projecting diametrically through the

collar and having an outlet directed through the coil, the collar having openings at the end of the channel and the channel being enlarged below the outlet to provide a priming cup, the top of the base having a marginal flange and having a flange surrounding and spaced from the collar.

7. In a hydro-carbon burner, a hollow base having an opening in its top, a collar around the opening, and a channel extending across the opening, a gasifying coil supported by the collar, the inner end of the coil projecting diametrically through the collar and having an outlet directed through the coil, the channel being enlarged below the outlet to provide a priming cup, the upper end of the coil projecting diametrically, and a reflector hung from the upper end of the coil over the said outlet.

8. In a hydro-carbon burner, a hollow base having an opening in its top, a collar around the opening, and a channel extending across the opening, the collar having openings at the ends of the channel and having notches in its upper edge at quadrature to the opening, a gasifying coil having its inner end projecting diametrically and seated in the said notches, the inner end of the coil having an opening directed through the coil, and the said channel being enlarged below the said outlet to provide a priming cup.

9. In a hydro-carbon burner, a hollow base having an opening in its top, a collar around the opening, and a channel extending across the opening, the collar having openings at the ends of the channel and having notches in its upper edge at quadrature to the openings, a gasifying coil having its inner end projecting diametrically and seated in the said notches, the inner end of the coil having an opening directed through the coil, the said channel being enlarged below the said outlet to provide a priming cup, the upper end of the coil projecting diametrically thereof, a reflector hung from the upper end of the coil over the outlet, and the top of the base having a marginal flange and a flange surrounding and spaced from the collar.

In testimony that we claim the foregoing as our own, we have hereto affixed our signatures in the presence of two witnesses.
